UNITED STATES PATENT OFFICE.

IRVIN S. BACH, OF EAST ROCKAWAY, NEW YORK, ASSIGNOR TO ADAMS-BACH HDKF.
MFG. CO., OF NEW YORK, N. Y., A CORPORATION OF NEW YORK.

HANDKERCHIEF SET.

1,419,658.

Specification of Letters Patent. Patented June 13, 1922.

Application filed April 13, 1921. Serial No. 461,063.

To all whom it may concern:

Be it known that IRVIN S. BACH, a citizen of United States of America, residing at East Rockaway, Long Island, New York, 5 U. S. A., has invented certain new and useful Improvements in Handkerchief Sets, of which the following is a specification.

This invention relates to handkerchief sets and particularly to handkerchief sets intended for children.

The object of the invention is to provide a handkerchief set comprising a plurality of handkerchiefs folded together in such a manner as to expose a portion of each handkerchief, upon which portion a suitable marking, design or designation may be printed, embroidered or otherwise applied so that all of said markings, designs or designations are visible at once.

More specifically the object of the invention is to provide a handkerchief set comprising a plurality of handkerchiefs, each having the name of a day of the week printed, embroidered or otherwise marked thereon, the handkerchiefs being folded together in such manner that the said names of the days of the week are all exposed in their serial arrangement, and so that the handkerchiefs having said names applied thereto may be removed in succession from the set without disturbing the remainder of the handkerchiefs, which remain in condition to show the balance of said serial arrangement until all are used.

The invention is illustrated in one form in the accompanying drawings, in which:

Figure 1 shows a handkerchief set indicating the days of the week in accordance with the present invention; and

Figure 2 is a view showing the manner in which the handkerchiefs are relatively arranged and superposed before folding, to expose portions of each thereof.

The set of handkerchiefs selected for illustration comprises seven handkerchiefs numbered 1 to 7 respectively, and which may be made of any suitable material and may be stitched, embroidered or otherwise ornamented in any suitable or desired manner.

The several handkerchiefs, at corresponding portions or corners thereof, are printed, embroidered or otherwise marked with the names of the days of the week, so that the set of handkerchiefs represents a week's supply, each marked for a particular day of

the week, and adapted to be individually removed from the set for use.

In arranging the handkerchiefs for folding, they are superposed one upon another in the manner indicated in Figure 2, so as to expose that portion or corner of each handkerchief upon which the name is printed or embroidered. It will be noted from Figure 2 that the entire set of handkerchiefs occupies a square of greater size than any individual handkerchief, the lowermost handkerchief 7 representing Saturday occupying a position at the lower right hand corner of the square. The handkerchiefs 6 and 5 representing Friday and Thursday respectively 60 are superposed upon the handkerchief 7 in the manner shown with the handkerchief 6 occupying the lower middle portion of the square and the handkerchief 5 occupying the lower left hand corner of the square. The handkerchiefs 4 and 3 representing Wednesday and Thursday are then superposed upon the handkerchiefs 5, 6 and 7 with the handkerchief 4 occupying the middle portion of the right hand side of the square and the handkerchief 3 occupying the upper right hand corner of said square. The handkerchief 2 representing Monday is superposed on the handkerchiefs 3 to 7, handkerchief 2 occupying the central portion of the square, 70 and the handkerchief 1 representing Sunday is then superposed on the remainder of the handkerchiefs, occupying the upper left hand corner of the square.

It will be seen that by arranging the handkerchiefs in this way, that portion or corner of each thereof having the name of the corresponding day of the week thereon is exposed so that the various names are simultaneously exhibited in substantially the order of their serial arrangement. The entire set of handkerchiefs arranged in accordance with Figure 2 is then folded first along the line I—I and then along the line II—II and by folding in this way the handkerchief set 95 shown in Figure 1 is obtained, the visible portion of the set comprising exposed portions or corners of a plurality of handkerchiefs, each having a name of a day of the week thereon.

The handkerchiefs, due to the manner of arranging and folding the same referred to above, may individually be removed from the set in the order of their serial arrangement without disturbing the handkerchiefs 100 105 110

remaining in the set, which continue to indicate the balance of the serial arrangement of the names marked thereon, that is the balance of the days of the week, until all the 5 handkerchiefs have been removed.

It will be understood that the invention is not intended to be restricted to the particular designations or names selected for illustration in the drawings as other markings, designs or designations may be used if desired. For example the days of the week 10 might be indicated by the numerals 1 to 7 printed, embroidered or otherwise marked upon the handkerchiefs, or other names, designations or characters might be marked thereon so as to be all exposed at the one time by the arranging and folding of the handkerchiefs in the manner described.

The invention provides a handkerchief set, 20 particularly adapted for the use of children, of novel, neat and attractive appearance. The set of handkerchiefs may be mounted on a card or backing and tied around with ribbon or the like, if so desired.

25 What I claim and desire to secure by Letters Patent is:—

1. A handkerchief set, comprising a plurality of handkerchiefs provided on corresponding portions thereof with markings 30 having a serial arrangement, said handkerchiefs being displaced relative to each other to expose all of said markings and said plurality of handkerchiefs being folded on lines at right angles to each other to permit removal one at a time without disturbing the 35 rest in the order of said serial arrangement.

2. A plurality of handkerchiefs provided on corresponding portions thereof with consecutive designations, and displaced relatively to each other so as to expose only the 40 portions having said designations thereon and all except one of said handkerchiefs folded together on lines at right angles to each other to permit removal of the handkerchiefs one at a time in consecutive order, 45 each without disturbing the remainder of the handkerchiefs.

3. A handkerchief set, comprising a plurality of handkerchiefs folded together in such manner that one corner only of each 50 handkerchief is visible, said handkerchiefs being removable one at a time without disturbing the rest, said visible corners having designations thereon, said designations being arranged in consecutive order corresponding to the order of removal of the handkerchiefs from the set.

4. A handkerchief set, comprising a plurality of handkerchiefs each having marked on a corner thereof the name of a day of 60 the week, said handkerchiefs being folded together to expose only the marked corners having said names thereon and so arranged as to permit removal of the handkerchiefs in consecutive order without disturbing the 65 rest.

In testimony whereof I affix my signature in presence of two witnesses.

IRVIN S. BACH.
